UNITED STATES PATENT OFFICE

JACOB TELLER, OF CHICAGO, ILLINOIS, ASSIGNOR TO TELLER CORPORATION, OF CHICAGO, ILLINOIS, A CORPORATION OF TENNESSEE

DESIGN FOR A COAL RANGE

Application filed April 11, 1930. Serial No. 35,224. Term of patent 7 years.

To all whom it may concern:

Be it known that I, JACOB TELLER, a citizen of the United States, and a resident of the city of Chicago, in the county of Cook and State of Illinois, have invented a new, original, and ornamental Design for Coal Range, of which the following is the specification, reference being had to the accom-

panying drawing, forming a part thereof.

In the drawing:

The figure is a perspective elevation of a coal range showing my new design.

I claim:

The ornamental design for a coal range as shown.

JACOB TELLER.
